United States Patent Office

Des. 227,807
Patented July 17, 1973

227,807

PORTABLE IMPRINTER

James M. Patterson, Jr., Fairfax County, Va., assignor to Farrington Business Machines Corporation, Springfield,
Va.

Filed May 1, 1972, Ser. No. 249,479

Term of patent 14 years

Int. Cl. D18—02

U.S. Cl. D64—11 B

FIG. 1

FIG. 2

FIG. 3

FIG. 1 is a rear perspective view of a portable imprinter showing my new design;

FIG. 2 is another perspective view thereof on smaller scale; and

FIG. 3 is a front elevational view thereof on larger scale.

I claim:

The ornamental design for a portable imprinter, as shown.
